UNITED STATES PATENT OFFICE.

HENRY C. BAINBRIDGE, OF BROOKLYN, NEW YORK.

DESIGN FOR WRITING-PAPER AND CARDS.

Specification forming part of Design No. **11,194**, dated May 13, 1879; application filed March 15, 1879.
[Term of patent 3½ years.]

To all whom it may concern:

Be it known that I, HENRY C. BAINBRIDGE, of Brooklyn, in Kings county, and State of New York, have invented a new and Improved Design for Writing-Paper and Cards, of which the following is a specification.

My design consists in a sheet of writing-paper or a card having a corner turned or folded over, and a representation of a knot arranged upon the turned-over corner, to give it the appearance of securing the said corner in its turned-over position.

The accompanying drawing represents a sheet of note-paper embodying my improved design.

A designates the sheet of paper, and *a* a corner thereof turned or folded over diagonally upon the face of the paper. Upon this turned-over corner *a* I arrange a representation of a knot in such manner as to give it the appear-

ance of securing the said corner in its turned-over position. I have here represented the knot as consisting of a bow-knot, *b*, formed of a piece of ribbon. The turned or folded over corner *a* then has the appearance of being fastened down by a piece of ribbon passing through it and tied in a bow-knot upon its face.

What I claim as my invention, and desire to secure by Letters Patent, is—

The design for writing-paper and cards, consisting in a representation of a knot arranged upon a turned or folded over corner of the same, and having the appearance of securing the said corner in its turned-over position, substantially as specified.

HENRY C. BAINBRIDGE.
